UNITED STATES PATENT OFFICE.

JOHN P. NORDSTROM, OF BROOKLYN, NEW YORK, ASSIGNOR OF ONE-THIRD TO ALLEN N. SPOONER AND ONE-THIRD TO DAVID M. TULLOCH, BOTH OF NEW YORK, N. Y.

FILE.

Application filed June 24, 1921. Serial No. 480,015.

To all whom it may concern:

Be it known that I, JOHN P. NORDSTROM, a citizen of the United States, residing at Brooklyn, in the county of Kings and State 5 of New York, have invented certain new and useful Improvements in Piles, of which the following is a full, clear, and exact description.

This invention relates to piles such as are utilized in pier and dock constructions, 10 foundations, etc., and particularly to piles intended to be sunk or driven in soft, marshy, boggy, loose sand or mud bottoms or strata. When piles are inserted into mud, quicksand, or a similar soft or boggy mass, 15 the mass packs around the pile and supports it, partly due to the skin or surface friction of the mass upon the surface of the pile and partly due to the area of the pile which 20 bears upon the mass.

An object of this invention is to provide a pile which when inserted into soft bottoms or strata will have an increased bearing power, and which may be sunk or driven in 25 the usual manner. A further and more particular object is to provide a pile having a maximum possible bearing area and surface friction, which will be strong, simple, effective, durable, inexpensive and have 30 greater sustaining power. Other objects and advantages will be apparent from the following description and the novel features of the invention will be particularly pointed out in claims.

35 In carrying the invention into practice, I increase the bearing area and surface friction by means of transverse lagging which is suitably secured to the sides of the usual piles, prior to sinking or driving them, 40 the details of the lagging and its manner of attachment being more particularly pointed out in connection with the following description of specific applications of the invention.

45 In the accompanying drawing:

Fig. 1 is a front elevation of a pile constructed in accordance with this invention.

Fig. 2 is a side elevation of a section of the pile.

50 Fig. 3 is a section of the same taken substantially along the line *a—a* of Fig. 2.

Fig. 4 is an elevation of a detail.

Fig. 5 is a perspective of the section shown in Fig. 2.

Fig. 6 is an elevation of a section of a pile 55 illustrating a modified form of lagging and manner of attachment and,

Fig. 7 is a section of the same taken along the line *b—b* of Fig. 6.

In the embodiment illustrated in Figs. 1 60 to 5, the body portion 1 of the pile, which may be of any suitable material such as wood, reinforced concrete, etc., is provided with a driving point 2. Notches 3 are provided on opposite sides of the body portion 65 and opposite one another, and are arranged in spaced relation (about every three feet) along the length of the part of the body portion which is driven or sunk into the soft strata or bottom. Auxiliary bearing or 70 lagging strips 4 are disposed in the notches to extend transversely of the body portion, one or two of the strips nearest the driving point being preferably shorter than the others so as to facilitate the penetration of 75 the pile. The strips may be temporarily held within the notches by spikes 5 or similar and suitable fastening means. Stirrups 6 which may be of metal, having a somewhat triangular shape embrace the projecting ends of the strips with a portion such as the base of each stirrup passing over the upper edges of the strips and with the ends or apex of each stirrup depending along the sides of the body portion. The converging arms or sides of the stirrups are provided with loops or eyes 7 which are superposed, and a single bolt 8, passing centrally through the body portion and the superposed loops or eyes at each side of the 90 body portion, serves to anchor the stirrups to the body portion. The stirrups confine the lagging or strips within the notches, prevent movement of the strips lengthwise of the body portion, and prevent breaking 95 off of the strips during the driving or sinking operation. Staples 9 may be passed over the base of the stirrup and into the body portion, where the latter is of wood, to prevent any movement of the base of the 100 stirrups away from the body portion.

In the embodiment illustrated in Figs. 6 and 7, the strips 10 comprise angle irons or members which are secured to opposite faces of the body portion by bolts 12 passing between the angle members and through the body portion of the pile. The bolts may have both ends threaded to receive clamp-

ing nuts and be cast in the body portion at the time the pile is cast, but preferably pipe sleeves 13 are cast in the body portion of the pile through which sleeves ordinary bolts 5 may be passed when the angle members or strips are attached. The angle members are preferably provided with apertures 14 elongated longitudinally of the members in order to compensate for any small inequalities in 10 the placing of the bolts or sleeves in casting the pile body portion. The strips are held against displacement from the body portion by the bolts and by the friction of the strips against the sides of the body portion 15 when the strips are firmly clamped thereto.

The uppermost lagging should be at a distance from the top which will permit it to come beneath the ways of the driver when the point is resting upon the upper surface 20 of the bottom or strata. The lagging not only increases the bearing surface of the pile but also increases the surface friction due to the increased area in contact with the mass in which it is placed, with a resulting 25 net increase in bearing power of the pile. The sides of the stirrups may, after they are assembled upon the body portion, be bent as at 6^a to tighten them slightly.

It will be obvious that various changes 30 in the details and arrangements of parts in the embodiments illustrated and described, may be made by those skilled in the art within the principle and scope of the invention.

35 I claim:

1. A pile comprising an elongated body portion, a pair of auxiliary bearing strips disposed on opposite sides of the body portion and opposite one another, and common means for securing both strips against movement endwise of the body portion.

40 2. A pile comprising an elongated body portion having notches on opposite sides thereof and opposite one another, auxiliary bearing strips disposed in said notches to extend transversely to the body portion, and means for securing the strips against movement endwise of the body portion and within the notches.

50 3. A pile comprising an elongated body

portion having notches on opposite sides thereof and opposite one another, auxiliary bearing strips disposed in said notches to extend transversely to the body portion, and common means for securing both strips 55 within the notches and against movement endwise of the body portion.

4. A pile comprising an elongated body portion, a pair of auxiliary bearing strips disposed on opposite sides of the body portion and opposite one another, and stirrups passing over the ends of both of the strips and anchored to the body portion below the strips to prevent endwise movement of the strips along the body portion.

5. A pile comprising an elongated body portion, a pair of auxiliary bearing strips disposed on opposite sides of the body portion and opposite one another, stirrups passing over the ends of both of the strips, and a single bolt passing through the body portion and lower ends of the stirrups for anchoring the strips to the body portion.

6. A pile comprising an elongated body portion, an auxiliary bearing strip extending transversely of and disposed against a face of the body portion, and stirrups passing over the extending ends of the strip and anchoring to the body portion below the strip.

7. A pile comprising an elongated body portion having notches on opposite sides thereof and opposite one another, auxiliary bearing strips disposed in said notches to extend transversely to the body portion, 35 means joining the corresponding projecting ends of the strips for confining the strips within the notches.

8. A pile comprising an elongated body portion, an auxiliary bearing member extending transversely of the body portion, and an anchoring element engaging with the member and anchored to the body portion below the member for preventing upward 90 endwise movement of the member along the body portion.

In witness whereof, I hereunto subscribe my signature.

JOHN P. NORDSTROM.
